MATTHIAS PLUM, OF NEWARK, NEW JERSEY.

ENVELOP-PRINTING MACHINE.

1,116,463.

Specification of Letters Patent. Patented Nov. 10, 1914.

Application filed February 1, 1911. Serial No. 605,848.

To all whom it may concern:

Be it known that I, LEWIS E. MORRISON, a citizen of the United States of America, and a resident of Newark, Essex county, New Jersey, have invented certain new and useful Improvements in Envelop-Printing Machines, of which the following is a specification.

This invention relates to improvements in envelop printing machines and the broad objects of the invention are to provide an automatic envelop feeding device for feeding several envelops side by side to the movable platen of a job press in combination with suitable tripping means in case one or all of the envelops should fail to reach the platen, and devices, actuated from the said tripping means for delivering the imprinted envelops separate from the printed ones.

Other objects will appear as this specification proceeds.

More particularly this invention is an improvement on an application filed by me on the 4th day of August, 1908, Serial Number 446,840 in which is disclosed a similar envelop printing mechanism having different means for separating the envelops at the delivery end than the ones disclosed in the present application, the specific objects of which are to provide simple and practical means for accomplishing the desired results.

To this end the invention comprises such parts and combinations of parts as are hereinafter described while reference is had to the accompanying drawings in which—

Figure 1 is a side elevation of a job press embodying the invention with the lower part of the frame omitted and parts in section. Fig. 2 is a diagram of the electrical circuit used in the tripping means. Figs. 3, 4 and 5 are detail views in parts of the tripping mechanism showing different positions thereof. Fig. 6 is a rear view of the parts shown in the last three figures. Fig. 7 is a front view of the envelop receptacles. Fig. 8 is a perspective view of the envelop separating and feeding mechanism. Fig. 9 is a detail view of the envelop receptacle. Fig. 10 is a detail view of parts of the tripping mechanism.

Referring to Fig. 8 the reference numeral 10 denotes a suitable framework for the support of the separating and feeding mechanisms. On the same is suitably

mounted another frame 11 carrying the envelop supporting members 12 in which it will be understood the envelops are supported in two piles side by side with their flaps downward. In the frame 11 slides a transverse bar 13 carrying the separating fingers 14 and which is operated, on each side of the press, by means of links as 15 connected to oscillating levers 16, suitably pivoted at 17 and operated in a manner to be pointed out later.

The separator fingers push the bottom envelops out over the shaft 18 onto the tapes 19. These latter pass around said shaft and another shaft 20 carried in the arms 21 journaled on the shaft 18. A cam 22 is secured to the arms 21 and rests on rollers carried by the levers 23 pivoted at 24 on the frame 10. The levers 23 rests on rollers 25 fast on the movable platen 26. The latter oscillates in the usual manner and through the above named instrumentalities the tapes are raised and lowered to receive and discharge the envelops to the platen. The shaft 18, hence the tapes are driven constantly toward the platen by suitable gearing indicated at 27. The usual guiding means are also provided.

In the swinging arms 21 there is pivoted a shaft 28 carrying stops 29 and rocked 30 from the usual platen locking cam 30 by means of levers 31, 31.

32 is a contact rod fast in arms 33 pivoted on the said shaft 28 and carrying movable contacts 34, see also Fig. 2, adapted to contact with fixed contacts 35 by gravity. The contacts are broken when the contact rod 32 is lifted through the instrumentality of arm 36, wire 37 and bell crank 38 which latter is operated from the cam 39 and for this purpose carries a cam roll 39. When the latter runs on the high part of the cam the contacts are open. When it is on the low part of the cam the arms 33 and rod 32 drop down and the contacts are made. The device is so timed that this occurs at the moment the separated envelops reach the stops 29 and thus are directly over the fixed contacts. Consequently, there can be no contacts made as the envelops prevent it. When, however, one or both of the envelops fail to be fed, the movable contacts drop directly on the fixed ones to close the circuit which includes a battery 40 and a magnet 41 having an armature 42 and 110

which actuates the trip of the press. When the stops 29 move up the contact is broken and the envelopes pass onto the platen.

I will next describe the delivery means.

43 indicates in general a suitable delivery gripper which is slidably carried on the aforesaid levers 23 and closed when brought into contact with the platen. The grippers, there being one for each pile of envelopes, are opened by rods 44. The movement back and forth of the grippers is effected by means of oscillating levers 45 suitably pivoted at the foot of the press. The said levers carries an arm 46, see Fig. 7, to 15 which is connected a link 47 the other end of which is pivoted on one of the connecting rods operating the form member 48. The other connecting rod 49 is seen in Fig. 1 and is pivoted to the aforesaid platen locking cam 30 fast on the main shaft 50 driven in the usual manner. The levers 45 further carry a rod 51 having an arm 52. The levers 16 for operating the separator fingers 14 are joined at their lower ends by 20 a rod 53 which rests against the levers 45. A spring 54 is fast to the said rod and the said arm 52. From this it will be understood that as the form member moves toward the platen, the gripper carrying levers 45 move away from the latter, to the right in Fig. 1, hence in turn cause the upper end of the levers 16 to move leftward in said figure to feed two envelopes to the tapes. The spring 54 takes up lost motion 25 between the said levers.

It is thought that the foregoing sufficiently describes the general operation and construction of the separating and feeding mechanism, the same having been described in detail in the application above referred to.

When the electrical circuit is closed as aforesaid, that is when either one or both of the envelopes fail to be fed and consequently there is nothing between the terminals 34 and 35, the contacting of these latter energizes the magnet 41 and the armature 42 is attracted. This movement of the armature is utilized to actuate the usual 45 tripping mechanism which in the type of press illustrated includes a tripping hand operated lever 55 pivoted at 56 and connected to a link 57 which is pivoted to an arm 58 fast on a rockshaft 59. Inside the 50 frame the said shaft carries a lever 60 having a stud 61 which travels in a slot 62 in a pivoted bell crank 63 which is connected by a link 64 to the arm 65 on the shaft 66. The shaft 66 is connected to the form and is 55 eccentrically mounted. This mechanism is well known and when the operator pulls the lever 55 into the position shown in Fig. 1 the shaft 66 is rotated in its eccentric bearings and the form is tripped, that is, it 60 cannot reach the platen.

The movement of the armature 42 is utilized to operate the tripping lever 55.

The magnet 41 and the armature is suitably mounted on the lever 55 as shown in Fig. 1. Above the magnet on the inside of the lever on a bracket 168 there is also pivoted at 67 a latch 68 which is normally held up by the weight of its arm and which is connected to the armature as shown. Also mounted on the lever 55 is a roll 69. On the connecting rod 49 there is pivoted a lever 70 having a hook 71 and a stud 72. The lever 70 moves with the connecting rod and slides on the roll 69 between the bracket 168 and the lever 55, during the normal operation of the press, but when an envelop misses and the armature is attracted, the latch 68 is pulled down, hence when the press closes the sliding lever engages the latch and carries the tripping lever 55 to the right and the form is tripped. On the return stroke the stud 72 pulls the tripping lever to the left thereby untripping the press. This happens every time an envelop misses, and of course the tripping lever 55 may be operated by hand as usual if desired.

When envelopes are being printed the various submechanisms operate of course as above described and two grippers will be provided for the delivery. And it will appear from Fig. 8 that when one or both of two envelopes fail to reach the platen then the tripping mechanism will operate. In case one envelop misses while the other is fed, this latter will of course pass through the press and be delivered by the gripper on the one side, but it will not be printed as the press has been tripped by the failure of the other envelop to reach the platen. Hence mechanism is provided for delivering the unprinted envelopes separate from the printed ones, and a suitable envelop receptacle has also been provided for quick removal of the envelopes. This mechanism 100 for thus separating the envelopes is actuated directly from the tripping mechanism and is shown in Figs. 1 to 7.

On a suitable cross bar of the machine there is mounted a bracket which supports a short shaft 75, see Fig. 6. The shaft carries a wheel 76 having two teeth 77 and 78. At the one end of the shaft there is secured an arm 79. Freely rotating on the shaft are two arms 80 and 81, one on each side of the wheel 76. The arm 80 carries a pawl 82 and is connected by a link 83 to the form member 48, hence oscillates constantly during the operation of the press. The arm 81 is connected by a link 84 to the aforesaid arm 60 of the tripping mechanism, hence the arm 81 moves only when the press is tripped. The arm 81 carries a pawl 85 and a disk 86. All of this mechanism remains stationary normally as shown in Fig. 3 except the arm 115 120 125 130

80 and pawl 82 which moves with the form member.

When the press is tripped the link 84 is moved to the right in Fig. 1 together with 5 the link 83 and the parts assume the position shown in this figure. The movement to the right of the link 84 brings the pawl 85 to the right of and into engagement with the tooth 78, which will be clear from an inspection 10 of Fig. 3 in which the parts are shown in the position just prior to the said movement. On the return stroke, to the left, the parts move to the position shown in Fig. 4 where it is seen that the pawl 85 by the 15 engagement with the tooth 78 has rotated the shaft 75 and pulled the arm 79 down, and has become disengaged from the tooth 78 because the latter is moved upwardly while the pawl 85 moves laterally away 20 from the disk 86. The pawl 82 has of course moved to the left also but has been unable to engage the tooth 77 by sliding on the disk 86. In other words the pawl 25 82 passes the tooth 77 as the latter rotates rightwardly and the pawl 82 leftwardly at the same time and at the end of the movement the pawl 82 rests on the wheel 76 as shown in Fig. 4. The pawl 82 now returns to the position shown in Fig. 5 and on the 30 next leftward stroke it will engage the tooth 77 on the wheel and return the arm 79 to its upward position. The arm 79 is stopped definitely in either of its positions by the coöperation of a spring pressed slide 35 88 which carries a roll 89 which in turn co-operates with a cam 90 on the shaft 75. In either of the two positions of the arm 79 the roll 89 enters a notch in the cam 90 to lock the shaft against rotation. The 40 movements of the arm 79 are utilized to operate the envelop receptacle as will appear presently.

The envelop receptacle, of which there are two side by side, comprises a box 91 having 45 a slide 92 suitably pivoted in the frame at 110. A trap door 93 is provided in the slide and is lifted by means of the pivoted links 94 and a lever 95 pivoted at 96 on the side of the slide and connected to the aforesaid 50 arm 79 by a strap 97. The trap door leads to a separate pocket 98. At the bottom of the box 91 there is hinged at 99 a shelf 100 normally held in the position shown by a spring latch 101.

55 During the normal operation of the press the grippers drop the envelops on the slide 92 and as the envelop box is jogged by reason of being connected to the rod 51 as shown, the envelops glide down into the box 91 and pile up. From time to time the spring latch 101 is opened, the shelf 100 is dropped and the batch of printed envelops conveniently removed. The envelops pile up in the box 91 with their printed side up 60 as they are received from the platen, and to

insure that the envelops do not turn around or become buckled, I provide rubber bands 112 or other suitable means for catching the edges of the individual envelop as the latter falls flat in the box. When, however, the 70 press is tripped the arm 79 is moved down as explained above and in turn pulls down the one end of the lever 95 which raises the trap door 93 so that as the unprinted envelop glides down the slide 92, it will pass 75 under the trap door 93 and into the pocket 98, so that there is no possibility of delivering a batch of envelops containing one or more unprinted ones. Of course, one or two 80 boxes 91 may be used as desired, when two boxes are used the pivots of the trap door are coupled in any suitable manner.

The foregoing is thought to fully explain this invention, its operation and its advantages. It will be seen that I have provided 85 very simple and practical means for separating the printed from the unprinted envelops, which, in its narrower aspects, is the object of the invention.

I do not wish to be limited to the exact 90 form shown or described as the invention is susceptible of changes which come within the legitimate and intended scope of the invention and the claims.

I claim—

1. In a printing machine, the combination 95 of means for simultaneously printing two envelops, means for preventing the one envelop from being printed if the other one fails to be placed in printing position, a plurality of envelop receptacles, one of said receptacles being adapted to receive the one single envelop if the other single envelop fails to be placed in printing position, a trap door interposed between the said receptacles and means for operating the said trap door to cause the one envelop to be delivered into the said last named receptacle.

2. In a printing machine the combination 100 of a platen, means for simultaneously placing two envelops on the said platen to be printed, a delivery mechanism for removing the envelops from the platen, a plurality of envelop receptacles, supporting means for receiving the envelops at the point of delivery, and for supporting the same while traveling toward the said receptacles, a movable member, and means for actuating the latter to project into the path of the envelops to cause one of the envelops to pass 105 into the one envelop receptacle when only one envelop reaches said platen.

3. In a printing machine the combination 110 of means for printing envelops, means for delivering printed envelops, a tripping mechanism, a plurality of envelop receptacles, a device normally inactive and adapted to form supporting means for the said envelops after the latter have passed 115 through the said printing means and dur-

95

105

110

115

120

125

130

ing their travel to the said receptacles, and means actuated by the said tripping mechanism for rendering the said inactive device active when the said matter fails to be printed and to cause the one receptacle to receive the unprinted matter.

4. In a printing machine, the combination of printing means including a platen, a feeding mechanism for feeding envelopes side by side to the platen, a delivery mechanism, an envelope receptacle for receiving the unprinted envelope from the said delivery mechanism, means for normally closing said envelope receptacle, and mechanism for operating the said means to open the said receptacle for the reception of the said unprinted envelopes.

5. In a printing machine, the combination of printing means including a platen, a feeding mechanism for feeding envelopes side by side to the said platen, a delivery mechanism, an envelope receptacle for receiving the unprinted envelopes from the said delivery mechanism, a movable member for normally closing said receptacle, and means for actuating said movable member when one of the said envelopes fails to be acted upon by the said feeding mechanism, and a separate receptacle for receiving the printed envelope from the said delivery member.

6. In a printing machine, the combination of a tripping mechanism, a printing mechanism means for delivering envelopes, a plurality of envelope receptacles, a support for receiving the envelopes at the point of delivery and for supporting the same while traveling toward said receptacle, a movable member forming a portion of said support and means for operating said member to cause unprinted envelopes to pass into a given one of the said receptacles when the said printing machine is tripped.

7. In a printing machine, the combination of printing means, a tripping mechanism, of means for delivering envelopes, a plurality of envelope receptacles, a support for receiving the envelopes at the point of delivery and for supporting the same while traveling toward said receptacle, a movable member forming a portion of said support and means for operating the said member to cause unprinted envelopes to pass into a given one of the said receptacles when the said printing

machine is tripped by the said tripping mechanism.

8. In a printing machine, the combination of means for printing envelopes, means for delivering the same, a plurality of envelope receptacles, supporting means for receiving the envelopes at the point of delivery and for supporting the same while traveling toward said receptacle, a movable member forming a part of the said supporting means and mechanism for operating said movable member to project into the path of the envelopes when the same fail to be printed.

9. In a printing machine, the combination of printing means, means for delivering envelopes, a box for receiving the envelopes located a distance away from the point of delivery, a supporting member for receiving the envelopes at the point of delivery and supporting the same during their travel to the said box, a movable member in said supporting member and means for operating said movable member to prevent unprinted envelopes from passing into the said box.

10. In a printing machine, the combination of printing means, means for delivering envelopes, an envelope receptacle, a slide integral with said receptacle and adapted to receive the envelopes from said delivery means, a movable member in said slide forming a part thereof and means for operating said movable member to prevent unprinted envelopes from passing into the said envelope receptacle.

11. In a printing machine the combination of printing means, means for delivering envelopes, an envelope receptacle, a support for receiving the envelopes from said delivery means and for guiding them to said receptacle, a member forming a part of said slide and interposed between the said receptacle and the place where the slide receives the envelopes from said delivery means and means for operating said member to prevent unprinted envelopes from passing into the said receptacle.

Signed at Newark, N. J., this 24 day of January, 1911.
